[57] CLAIM

The ornamental design for a hamburger cooker, as
shown.

DESCRIPTION

FIG. 1 is a top perspective view of a hamburger cooker
showing my new design;
FIG. 2 is a bottom perspective view of a hamburger
cooker showing my new design;
FIG. 3 is a plan view on an enlarged scale of the inside
of the bottom of the hamburger cooker;
FIG. 4 is a cross-sectional view along the path defined
by arrows 4 in FIG. 3;
FIG. 5 is a plan view on an enlarged scale of the inside
of the top of the hamburger cooker; and
FIG. 6 is a cross-sectional view along the line 6—6 of
FIG. 5.
